UNITED STATES PATENT OFFICE.

HARVEY A. CALMUS, OF PITTSBURGH, PENNSYLVANIA.

HEN-MARKER.

1,350,209.

Specification of Letters Patent. Patented Aug. 17, 1920.

Application filed March 16, 1920. Serial No. 366,182.

To all whom it may concern:

Be it known that I, HARVEY A. CALMUS, a citizen of the United States, residing at Pittsburgh, in the county of Allegheny and 5 State of Pennsylvania, have invented new and useful Improvements in Hen-Markers, of which the following is a specification.

The object of my present invention is the provision of a simple, inexpensive, easily 10 stalled and reliable apparatus for marking laying hens so that the same may be readily distinguished from brooders--i. e., hens that are disposed to set.

To the attainment of the foregoing, the 15 invention consists in the improvement as hereinafter described and definitely claimed.

In the accompanying drawings, hereby made a part hereof:

Figure 1 is a side elevation of my novel 20 marking apparatus.

Fig. 2 is a horizontal section taken in the plane indicated by the line 2--2 of Fig. 1, looking downwardly.

Fig. 3 is a vertical section illustrative of 25 the dye receptacle, the valve for controlling the discharge thereof, and the arrangement of the valve stem relatively to the thrust rod for opening the valve.

Similar numerals of reference designate 30 corresponding parts in all of the views of the drawings.

Among other elements my novel apparatus comprises an upright frame bar 1 adapted to be connected in fixed relation to 35 the wall of a coop, or any other appropriate support.

Fixed to and reaching forwardly from the frame bar 1 is a platform bar 2.

Also fixed to and reaching forwardly 40 from the bar 1 is an overhanging arm 3 that is disposed above the platform bar 2 about the proportional distance illustrated, and is suitably braced as shown. The said bars 1, 2 and 3, constitute the main frame of 45 my novel apparatus, and it will be noticed that the platform bar 2 is also appropriately braced. In the preferred embodiment of my invention, the bracing of the bar 2 and the overhanging arm 3 is effected 50 through the medium of diagonal braces 4 disposed at opposite sides of the platform bar 2 and the overhanging arm 3, respectively.

At 5 are standards fixed to and rising

from the platform bar 2 at an intermediate 55 point in the length thereof.

Fulcrumed at an intermediate point in its length between the standards 5, is a vertically swinging lever 6 on the outer arm of which is carried a nest 7.

Interposed between the platform bar 2 and the outer arm of the lever 6 is a spring 8, and bearing on the inner end portion of the lever 6 and movable vertically between the braces 4 is a vertical thrust rod 9, the 65 upper end portion of which is tapered, as indicated by 10.

Suitably supported around and in spaced relation to the nest 7 is a stationary guard 11. This guard 11 has for its function to 70 prevent any depression whatsoever of the outer arm of the lever 6 until the hen is disposed in the nest 7.

Carried on the outer portion of the overhanging arm 3 is a dye receptacle 12 having 75 a discharge 13 normally closed by a valve 14 that is normally held to its seat through the medium of a spring 15 opposed to its stem 16. The rear end of the said stem is opposed to the tapered or beveled upper 80 portion 10 of the thrust rod 9.

In the practical operation of my novel apparatus it will be manifest that the weight of the hen in the nest 7 will depress the outer arm of the lever 6, and accordingly 85 will raise the inner arm of said lever and the thrust rod 9. In consequence of this, the valve 14 will be moved outwardly so as to bring about the dropping of a sufficient quantity of dye on the back of the hen in 90 the nest to adequately mark the hen. In this connection it will be noticed that when the valve 14 is thrust outwardly, its port 17 will be momentarily registered with the discharge of the receptacle 12, and that immediately afterward the discharge 13 will be closed by the valve. From this it follows that on the operation of the valve, only a drop or two of the dye will be deposited on the back of the hen, though sufficient to 95 adequately mark the hen. After the forward movement and also after the rearward movement of the valve to restore the same to its normal position, the discharge 13 of the receptacle 12 will be closed to prevent 100 waste of the dye or marking material employed.

Below the registration point of the ports

17 and 18, the arm carries a conduit or spout 18 for the downward passage of the dye.

Having described my invention, what I claim and desire to secure by Letters-Pat-
5 ent, is:

1. A hen marking apparatus comprising an upright frame bar, a platform bar fixed to and reaching forwardly from the lower portion of the upright bar, an overhanging 10 arm fixed to and reaching forwardly from the upper portion of the upright bar, diagonal braces spaced apart and connected to the upright bar and the platform bar, similar braces spaced apart and fixed to the 15 upright bar and the overhanging arm, a vertically swinging lever fulcrumed at an intermediate point of its length above the platform bar, a nest carried by the outer arm of said lever, a spring interposed be- 20 tween the platform bar and the outer arm of the lever, a guard carried by the frame and surrounding and spaced from the nest, an upright thrust rod movable upwardly by the inner arm of the lever and guided 25 between the braces and having a tapered

upper portion, a receptacle carried by the overhanging arm in position above the nest and having a discharge, and a spring-pressed valve carried by the overhanging arm and normally closing the discharge of 30 the receptacle and operable by upward movement of the thrust rod to momentarily open the discharge of the receptacle.

2. A hen marking apparatus comprising a frame, a lever, a nest on the outer arm of 35 the lever and movable downwardly by the weight of a hen, means to yieldingly support the nest, a receptacle for marking substance connected with the frame and having a discharge arranged above the nest, an up- 40 right thrust rod movable upwardly by the inner arm of the lever and having a tapered upper portion, and a spring-pressed valve normally closing the discharge of the receptacle and operable by upward movement 45 of the thrust rod to momentarily open the discharge of the receptacle.

In testimony whereof I affix my signature.

HARVEY A. CALMUS.
